ABSTRACT: A floating retainer for water carried debris of various types, including liquid debris such as oil from ships, offshore drilling operations, and the like. The retainer includes an elongated vertically orientatable gathering skirt, the upper edge of which defines an elongated pocket for the reception of buoyant float material. The lower edge defines a ballast-receiving pocket. Interengaging male and female ends are provided in conjunction with joining collars for the tying together of two or more retainers.

RETAINER FOR FLOATING DEBRIS

The invention herein is generally concerned with the gathering, retention and removal of floating debris of various types, and more particularly relates to a floating retainer capable of being extended over a predetermined body of water in a manner so as to catch and retain debris therein.

While debris retainers of the same general type as herein contemplated are known, such retainers incorporate many disadvantages which affect the use and efficiency thereof. For example, the basically heavy and bulky nature of the known retainers make both the storage and handling thereof difficult. By the same token, notwithstanding the weight and bulk of these retainers, such often incorporate a relatively low tensile strength, both in the individual sections and in the joining portions, thus limiting the lengths which can be effectively used, both as a standing barrier and as a towed gathering unit.

It is a primary object of the instant invention to provide a unique retainer which avoids the deficiencies noted supra. More particularly, it is an object of the instant invention to provide a retainer which is capable of being rolled, coiled, or placed on reels for easy compact storage. By the same token, the retainer of the instant invention is to combine both a high tensile strength, approximately 4,200 pounds per square inch, with a light weight of approximately 18 ounces per running foot whereby one man can easily handle up to 100 feet of the retainer, and the retainer towed in sections of up to 2 miles in length.

In conjunction with the above objects, it is also a significant object of the instant invention to provide a retainer which is economical to manufacture and of a highly durable nature.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a top plan view of a section of a debris gathering barrier formed by utilizing the retainer of the instant invention, the barrier being anchored in a fixed location;

FIG. 2 is a perspective view of the retainer of the instant invention;

FIG. 3 is an enlarged perspective view of the joined ends of a pair of adjacent retainers;

FIG. 4 is an enlarged transverse cross-sectional view taken substantially on a plane passing along line 4-4 in FIG. 2;

FIG. 5 is an enlarged partial cross-sectional view taken substantially on a plane passing along line 5-5 in FIG. 3; and

FIG. 6 is an elevational view of the adjoining male and female ends of a pair of adjacent retainers.

Referring now more specifically to the drawings, reference numeral 10 is used to generally designate the retainer comprising the instant invention. The retainer 10, normally constructed in lengths of approximately 54 feet, includes a full length 10 inch retaining skirt 12, an upper float section 14, and a lower ballast section 16.

The retainer 10 is formed utilizing, preferably, a sheet of 14 ounce cotton canvas, treated so as to be water, mildew and rot resistant, folded so as to define a circular float material receiving pocket 18 from which a pair of adjacent skirt forming panels 20 depend. One of the panels 20 is substantially wider than the other panel with the lower edge portion thereof being upwardly folded so as to define a flap 22 which overlies the outer face of the second panel, and at the same time provides a full-length ballast retaining pocket 24 along the lower edge of the skirt 12. The depending panels 20 are stitched together immediately below the pocket 18, normally by at least two rows of stitching 26. In addition, stitching 28 is also provided along the skirt 12 above the ballast portion 16 and through both the two panels 20 and the overlying panel flap 22 which flap, incidentally, is approximately 3 inches in height.

The float material-receiving pocket 18 is approximately 4 inches in diameter and preferably filled with expanded

polyethylene foam. The ballast 30, received within the full length ballast pocket 28 of the ballast section 16, is preferably $\frac{3}{8}$ -inch diameter lead wire, the weight thereof being sufficient so as to, in combination with the float section 14, properly orientate the retainer 10 for the interception and gathering of floating debris of various types.

The retainer 10 includes a male end 32 and a female end 34, the canvas material, at both ends, being inwardly folded and stitched so as to define reinforced end portions. The 10 aforescribed retainer construction, including the float material, ballast 30, panel flap 22 and stitching, is continuous within the male end 32. At the female end 34, on the contrary, the float material, ballast wire, panel flap and stitching terminate approximately 6 inches short of the extreme end, providing in effect a mouth for the reception of the male end 15 therein as will be best seen in FIGS. 3 and 5. Each of the skirt-forming panels 20, at the female end, is provided with a pair of vertically spaced $\frac{3}{8}$ -inch brass grommets 36 which, upon the 20 reception of the male end 32 of an adjacent retainer 10 therein, align with and to the opposite sides of a pair of vertically spaced $\frac{3}{8}$ -inch grommets 38 through the stitched panels 25 at the male end 32, the lower one of the grommets 38 actually extending through the upwardly directed panel flap 22. It will 30 of course be appreciated that the male end grommets 38 are positioned inwardly from the extreme end of the retainer 10 approximately 6 inches for alignment with the two pairs of grommets 38 orientated quite closely adjacent the extreme 35 end of the retainer 10 at the female end 34. In addition, it will be noted that the canvas sheet is double stitched in alignment with the various grommets so as to provide additional reinforcing thereabout, the retainer also being provided with a double row of stitching transversely thereacross at and in alignment with the foreshortened end of the flap 22 at the 40 female end 34. The actual securing together of the telescopically internested end portions of the panels 20 of a pair of adjacent retainers 10 to be joined end to end is effected by utilizing $\frac{3}{8}$ -inch nylon rope 40 extended and tied therethrough as indicated in FIG. 3.

45 The basic retainer 10, at the opposed ends 32 and 34, is also provided with a pair of outwardly directed joining collars 42. Each collar, positioned about the float-receiving pocket 18, has the inner edge 44 thereof inwardly and reversely turned and permanently stitched to the pocket forming canvas. The second edge 46 of each collar 42 opens toward the corresponding extreme end of the retainer 10 and is unsecured and relatively wide, appropriate edge notches 48 being provided therein so as to enable a slight spreading of this edge as compared to the tightly held and stitched securing edge of the collar. Finally, each collar is provided with a series of $\frac{3}{8}$ -inch 50 diameter brass grommets 50 mounted peripherally therein just inward of the open mouth forming edge 46. With reference to FIGS. 3 and 5 in particular, the collars 42 are so orientated on the respective ends so as to, upon the telescopic mounting of the adjoining ends of a pair of retainers 10, one collar 42 is telescopically received within the collar 42 on the adjoining retainer with the collar grommets 50 aligning for the extension of appropriate binding nylon rope 52 therethrough. This rope 55 52 can, rather than being separate from the panel securing rope 40, actually constitute a continuation thereof. Incidentally, it will be appreciated that the opposed sides of each of the collars 42, as it encircles the float section 14, terminate at the skirt 12 and are left unsecured for the telescopic reception of one collar within the other.

60 With reference to FIG. 1, it will be noted that one contemplated use of the retainer of the instant invention is in conjunction with a plurality of similar retainers in the formation of an elongated barrier secured to anchors 54 by appropriate anchor cables 56 engaged between the anchors 54 and grommeted anchor straps 58 stitched to and depending from the retainer skirts 12 at spaced points along the individual retainers 10.

65 From the foregoing, it should be appreciated that a highly unique retainer for floating debris has been defined. This
